US0D1077970S

(12) **United States Design Patent** (10) **Patent No.:** **US D1,077,970 S**
(45) **Date of Patent:** **** Jun. 3, 2025**

(54) **KNIFE HANDLE**

(71) Applicant: **Magpul Industries Corp.**, Austin, TX (US)

(72) Inventors: **Nicholas Kielsmeier**, Denver, CO (US); **Clinton Wade Lynch**, Erie, CO (US)

(73) Assignee: **Magpul Industries Corp.**, Austin, TX (US)

(**) Term: **15 Years**

(21) Appl. No.: **29/857,945**

(22) Filed: **Oct. 26, 2022**

(51) **LOC (15) Cl.** **22-02**

(52) **U.S. Cl.**

USPC **D22/118**

(57) **CLAIM**

The ornamental design for a knife handle, as shown.

DESCRIPTION

FIG. 1 is a left, front, top perspective view of an embodiment of a tang of the knife;

FIG. 2 is a right, rear, bottom perspective view of the embodiment;

FIG. 3 is a front elevation view of the embodiment;

FIG. 4 is a back elevation view of the embodiment;

FIG. 5 is a right elevation view of the embodiment;

FIG. 6 is a left elevation view of the embodiment;

FIG. 7 is a top view of the embodiment; and,

FIG. 8 is a bottom view of the embodiment.

The shade lines in the Figures show contour and not surface ornamentation.

The broken lines showing portions of the design in all figures are included for the purpose of illustrating environment and do not form a part of the claimed design.

The unshaded areas between solid line and broken line structure form no part of the claimed design.

1 Claim, 7 Drawing Sheets
